GARTER

Jeremiah C. Day, Lexington, Ky.

Application August 21, 1934, Serial No. 740,822

3 Claims. (Cl. 241—6)

The invention relates to a garter construction and more especially to a supporter for men's hose.

The primary object of the invention is the provision of a garter or supporter of this character, wherein the leg embracing member is of a construction that contact will be had with the limb at points thereof, so as to eliminate any possibility of interference with the circulation in the limb, as by stoppage of the flow of the arteries or veins, and at the same time will comfortably support the hose and avoid any possibility of discomfort to the wearer of such garter or supporter.

Another object of the invention is the provision of a garter or supporter of this character, wherein the construction thereof enables self-adjustment when worn and such garter or supporter is capable of fitting to limbs of various sizes according to the requirements of the wearer thereof.

A further object of the invention is the provision of a garter or supporter of this character, wherein all metal parts as may be included therewith are covered with a soft pliable substance, either fabric, leather covering or the like, so that in the wearing of the garter or supporter there is no possibility of contact of the metal parts with the skin or the limb and in this fashion bruising or injury, by cutting or otherwise, to the limb is avoided and at the same time rendering maximum comfort to the user of the garter.

A still further object of the invention is the provision of a garter or supporter of this character, wherein the hose attaching portions thereof are so constructed as to maintain the leg embracing member in proper position at all times and thus the garter can be perfectly worn for the purposes intended thereof.

A still further object of the invention is the provision of a garter or supporter of this character, wherein a maximum range of adjustment is assured for satisfying the service of the said garter or supporter with hose or socks of different leg portion lengths and also for the fastening of the garter in place upon the leg of the wearer.

A still further object of the invention is the provision of a garter or supporter of this character which can be readily and conveniently applied to the leg of a wearer or removed therefrom and while being worn will assure comfort and at the same time the leg covering, such as the trousers, will be prevented from contact with the large part of the leg and thus avoid damage to the trousers resultant from perspiring or otherwise.

A still further object of the invention is the

provision of a garter or supporter of this character which is extremely simple in its construction, thoroughly reliable and efficient in its purposes, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

In the accompanying drawing:

Figure 1 is a perspective view of the leg of a person, showing the hose thereon and the garter or supporter constructed in accordance with the invention in position.

Figure 2 is a horizontal sectional view through the leg embracing member of the garter of slightly modified form.

Figure 3 is a fragmentary rear elevation showing the garter in place upon the limb or leg and accentuating the contacting feature thereof.

Figure 4 is a fragmentary elevation showing in detail the separable fastener for the garter.

Figure 5 is a sectional view on the line 5—5 of Figure 1.

Similar reference characters indicate corresponding parts throughout the several views in the drawing.

Referring to the drawing in detail, the garter comprises a pair of pads 10, each being preferably made from leather, having the elongated formation as disclosed in Figure 1 of the drawing, and provided with the reversely tapered ends 11, 35 it being understood, of course, that these pads may be made from any other suitable material. These pads lengthwise thereof are provided with guideways 12 for slidably accommodating the inset curved end portions 13 of a resilient or spring clip 14, made of inherent resilient strip-like metal having the bights 15 insetting the end portions 13, as is clearly shown in Figure 2 of the drawing. These end portions 13 give to the pads 10 an outwardly or laterally outward arch formation so 45 that in the wearing of the garter actual contact with the leg 16 of a wearer will be had at the fore points 17 and the clip 14 intermediate of these end portions, due to the curvature thereof, and the bights 15 will be offset and out of possible 50 contact with the rear portion of the leg or limb 16 when the garter or supporter is worn.

The clip 14 is contained within an elastic case- 55 ment 18, preferably of fabric or fabric and leather, so that the same may be extended or con-

tracted, and the ends of this casement are made secure, at 19, within the ways 12 constituted in the pads 10, so that it is impossible for the separation of the clip 14 and pads 10, yet these parts 5 are self-adjusting with respect to each other in the wearing of the garter or supporter. It is, of course, to be understood that the ends 13 are free within the ways 12 in the pads 10 and also within the casement 18.

10 One of the pads 10, at the fore part of the same, has fitted therein an eye member 20 for detachable engagement with a fastener, in this form a hook 21, carried upon an adjustable strap 22 fixed to the other pad 10 and in this fashion 15 the garter is detachably engaged in place to encircle the limb or leg 16, as is clearly apparent in Figure 1 of the drawing.

Carried by the pads 10 are the substantially 20 Y-shaped hangers or suspension pieces 23 with which are adjustably connected through the medium of a slide as at A hose attaching devices 24 of any approved type, so that the hose 25 can be engaged thereby for the holding of the hose in place upon the wearer.

25 The leg encircling or embracing member which includes the pads 10, the clip 14 and the fastening medium at the fore part of the garter constitutes the essentials of the invention because by reason of the construction of the pad and the clip there will be had a two-point contact of these pads 10 with the leg 16 and such points of contact are at localities of the limb or leg to have both the pads and the clips saddle the leg to avoid pressure of the garter while being worn 30 upon the leg to retard free circulation therein or to shut off artery or vein flow during the wearing of the garter, and particularly under leg action. It should be noted that the strap 22, at the point of fastening medium for the garter to have the same about the leg, is located at the 35 bone area of the leg and by reason of the elasticity due to the make-up of such strap 22, which is

preferably made from fabric and rubber, the same will freely yield or give to avoid any undue pressure upon the leg at such point, there being perfect comfort in the wearing of the garter or supporter and the same serving to hold the hose or sock 25, as is required in the wearing thereof.

5 What is claimed is:

1. In a garter of the character described, a pair of pads, each having contact areas with a leg of a person at portions thereof free of veins and arteries therein, a clip cooperating with the pads and out of contact with the leg at the rear thereof, means for adjustably connecting the pads at the fore of the leg, and means for attachment of a hose or sock with the pads.

10 2. In a garter of the character described, a pair of pads, each having contact areas with a leg of a person at portions thereof free of veins and arteries therein, a clip cooperating with the pads and out of contact with the leg at the rear thereof, 20 means for adjustably connecting the pads at the fore of the leg, means for attachment of a hose or sock with the pads, means for adjustment of the first-named means, means for adjustment of the second-named means, and an expandable and contractible casement for the clip and having its 25 ends fixed within the pads.

3. In a garter of the character described, a pair of pads, each having contact areas with a leg of a person at portions thereof free of veins and arteries therein, a clip cooperating with the pads and out of contact with the leg at the rear thereof, means for adjustably connecting the pads at the fore of the leg, means for attachment of a hose or sock with the pads, means for adjustment of the first-named means, means for adjustment of the second-named means, an expandable and contractible casement for the clip and having its ends fixed within the pads, and a separable fastener for the first-named means.
